UNITED STATES PATENT OFFICE.

JOHN I. REYNOLDS, OF CLEBURNE, TEXAS.

RAILWAY-SWITCH.

No. 889,485.

Specification of Letters Patent.

Patented June 2, 1908.

Application filed September 17, 1907. Serial No. 393,272.

To all whom it may concern:

Be it known that I, JOHN I. REYNOLDS, a citizen of the United States of America, residing at Cleburne, county of Johnson, State 5 of Texas, have invented certain new and useful Improvements in Railway-Switches, of which the following is a specification.

This invention relates to new and useful improvements in railway switches and has 10 primarily for its object to produce a novel device of this kind wherein the switch or switch tongue is prevented from being turned up or sprung by cars running through it when not properly lined.

15 It is a further object of the invention to provide a novel device whereby cars will be transferred to the proper rail without depending upon the switch tongue.

Furthermore, it is the object of this invention to produce a device of the characters noted, which will possess advantages in 20 points of simplicity, efficiency and durability, proving at the same time comparatively inexpensive to manufacture.

25 With the foregoing and other objects in view, the invention consists in the details of construction and in the arrangement and combination of parts to be hereinafter more fully set forth and claimed.

30 In describing the invention in detail, reference will be had to the accompanying drawings forming part of this specification wherein like characters denote corresponding parts in the several views, in which—

35 Figure 1, is a fragmentary view of a railroad track showing the invention applied; Fig. 2, is a side elevation of Fig. 1; Fig. 3, is a 40 sectional view illustrating the invention in detail; and Figs. 4 and 5, are detail views of certain features of the invention.

In the drawings 1, denotes the rails and 2, the tongue portions of the switch. The invention proper is applied a distance in advance of the tongues and is intended to 45 transfer the cars from one rail to the other independently of the switch tongues. This is found necessary as often the switch tongues do not properly line and therefore cause mis-haps of a serious nature.

50 Resting upon and secured to two cross ties 3, on the inner side of the rails at the proper location, are the base blocks 4, which are provided with the guide-ways 5, in which are movable the frogs 6, said movement of the 55 frogs being at right angles to the rail. Each

of the frogs 6, is provided with an overlapping portion intended to rest above the rail and the upper portion of the frog is provided with a groove 7, in which the flanges of the car wheels will ride and which will guide 60 the wheels from one track to the next as will, it is thought, be fully understood. When one of the frogs is above one rail, the opposite frog is free at a point away from the rail. These frogs may be moved in any desired 65 manner, but it has been found best that they be moved simultaneously with the throw of the switch tongues. In order that this may be done, the switch lever 8, is prolonged or extended and pivoted to the plate 9, positioned 70 between the frogs. Engaging this plate are the arms 10, which in turn engage the frogs. Therefore, it will be seen that when the lever 8, is moved, the frogs will be given a corresponding movement in the 75 proper direction. In practice it has been found best to have the frogs 6, movable on the plates 11, resting on the base block 4. These plates are acted upon by the springs 12, which so elevate the frog as to allow 80 them to pass freely over the top of the rails.

Interposed between the rails of the main track and the diverging rails are the blocks 13, which are intended to bridge the space between the rails 1 and 2, when the invention 85 is in operation. These blocks are moved into and out of position vertically and this movement is attained by the cam levers 14, operative in unison with the plate 9. These cam levers contact with the under 90 surface of the block and elevate them. The block 13, which may be inoperative will fall beneath the rail by its own gravity or by the contact of a wheel passing over the rails as will, it is thought be understood. 95

For the purpose of illustrating the operation of the device, the rails in Fig. 1, will be lettered *a*, *b*, *c*, and *d*. Should a train be riding on rails *a* and *c* and the switch tongue 2, should not be properly set the train would 100 engage the frog 6, resting on the rail 3 and be guided by the frog to the rails *b* and *d*. Should the switch be drawn in a direction opposite to that illustrated in the figure, the train on the rails *a* and *c* is free to pass continuously on said rails, but should a train be on tracks *b* and *d* they would engage the second frog 6 which would guide the train from tracks *b* and *d* to tracks *c* and *a*, it being 105 understood of course that with the throwing 110

of the switch, the position of the frogs will be changed from what is shown in the drawings.

When a train is passing over one of the blocks 6, the same is forced down within an offset in the base or foundation blocks and the spring 12, before referred to will elevate the frog from this offset when the weight of the train is removed from the frog. It may 10 also be necessary to provide a suitable locking mechanism for holding the frogs 6, against inward movement. For this purpose any desired mechanism may be employed. It has been found best in practice 15 to operate this locking mechanism of the frogs from a stand to one side of the track.

What I claim is:

1. In combination with converging rails of a railroad track, movable means for causing a vehicle moving on certain of the rails to pass over said rails to the remaining rails, a portion of said moving means being movable vertically with relation to the rails.

2. In combination with converging rails of 25 a railroad track, movable means for causing a vehicle moving on certain of the rails to pass over said rails to the remaining rails, a portion of said moving means being movable vertically with relation to the rails, a second 30 portion of the movable means being movable transversely with relation to the rails.

3. In combination with converging rails of a railroad track, means for causing a vehicle moving on certain of the rails to pass 35 over said rails to the remaining rails, and means for bridging the space between the rails where said vehicle passes over one rail to the other.

4. In combination with converging rails of a railroad track, means for causing a vehicle moving on certain of the rails to pass over 40 said rails to the remaining rails, and movable means for bridging the space between the rails where said vehicle passes over one rail to the other.

5. In combination with converging rails of a railroad track, means for causing a vehicle moving on certain of the rails to pass over 45 said rails to the remaining rails, and vertically movable means for bridging the 50 space between the rails where said vehicle passes over one rail to the other.

6. In combination with converging rails of a railroad track, movable means for causing a vehicle moving on certain of the rails 55 to pass over said rails to the remaining rails, and movable means for bridging the space between the rails where said vehicle passes over one rail to the other, both of said movable means being operative simultaneously.

7. In combination with converging rails of a railroad track, means movable transversely with relation to the rails for causing a vehicle moving on certain of the rails to 65 pass over said rails to the remaining rails, and vertically movable means for bridging the space between the rails where said vehicle passes over one rail to the other.

In testimony whereof, I affix my signature 70 in the presence of two witnesses.

JOHN I. REYNOLDS.

Witnesses:

FLORENCE BROWN,
MASON CLURLAND.
